YARN WINDING

Svend A. Petersen, Brooklyn, N. Y., assignor to Celanese Corporation of America, New York, N. Y., a corporation of Delaware

Application February 5, 1953, Serial No. 335,226

11 Claims. (Cl. 242—18)

This invention relates to a yarn winder and relates more particularly to a horizontal yarn winder and to a damping mechanism employed therein.

For the winding of yarn packages such as cheeses and the like, it is the general practice in the textile industry to employ a so-called horizontal winder. This winder comprises a supporting arm that is pivotally mounted at one point and carries, at a point spaced from its mounting, a suitable freely rotatable mandrel for engaging a yarn package. There is also provided in said winder a positively driven roll whose axis lies parallel to the axis of the mandrel and against which the yarn package bears. The rotation of the positively driven roll drives the yarn package through friction at a constant peripheral speed to wind the yarn thereon at a constant linear rate. The yarn is distributed axially along the package being formed by the winding operation in any desired manner by means of a suitable traverse mechanism that guides the yarn onto the yarn package.

The winding of the yarn onto the yarn package is carried out at speeds of up to 1000 meters per minute or more, and at rotational speeds of up to 4400 revolutions per minute or more. When, at these speeds, the yarn windings on the package depart from a circular cross-section as, for example, by developing a high spot, there is tendency for the yarn package to bounce away from the drive roll. As a result, the pressure between the yarn package and the drive roll will fluctuate thereby introducing further irregularities into the yarn windings. The tendency of the yarn package to bounce away from the drive roll not only results in the production of irregular packages, but also acts to limit the maximum speed at which the horizontal winder can be operated.

It is an important object of this invention to provide a yarn winder which will be free from the foregoing and other disadvantages and which will be especially simple in construction and efficient in operation.

A further object of this invention is to provide in a horizontal yarn winder a hydraulic damping mechanism for maintaining a uniform pressure between the yarn package and the drive roll.

Another object of this invention is to provide an improved hydraulic damping mechanism.

Other objects of this invention, together with certain details of construction and combinations of parts, will be apparent from the following detailed description and claims.

According to the present invention, there is provided a yarn winder comprising a movable supporting arm that carries a freely rotatable mandrel for engaging a yarn package. The yarn winder also includes a positively driven roll which is in frictional engagement with the yarn package and serves to drive the same at a constant peripheral speed. The movable supporting arm is operatively connected to a hydraulic damper which will interpose little or no resistance to slow movements of the supporting arm, but which will interpose a considerable

2

resistance to rapid movements of said arm. Thus, as the diameter of the yarn package builds up there will be little or no resistance to the movement of the supporting arm necessary to permit the axis of the mandrel carrying the yarn package to move away from the drive roll. However, in the event that any irregularities develop in the yarn package which would tend to cause the yarn package and the supporting arm carrying the same to bounce, the hydraulic damper will impose a considerable resistance to such movement. As a result, the tendency of the yarn package to bounce will be substantially eliminated and, in addition, the pressures developed by the hydraulic damper between the drive roll and the yarn package will tend, upon the addition of further windings to the package, to restore the said package to a truly circular cross-section.

When the yarn package is filled, the mandrel carrying said package is moved away from the drive roll to break the frictional contact between the yarn package and the drive roll. The yarn package is then doffed. To eliminate the resistance by the hydraulic damper to the movement of the yarn package to the doffing position, means are provided for rendering said hydraulic damper substantially inoperative during such movement. Stop means are provided for definitely fixing the position of the yarn package during the doffing operation. To prevent the yarn package or the means carrying the same from striking the said stop means with sufficient force to cause damage, the hydraulic damper may again be rendered operative immediately before the yarn package reaches the doffing position so that the movement of said yarn package to said position will be cushioned. After the doffing of the yarn package, the mandrel is moved to bring a new yarn package support into frictional contact with the drive roll for the winding of another yarn package. During such movement, means are provided for greatly reducing the resistance of the hydraulic damper so that said movement may be effected rapidly and without the use of excessive force.

In one form of apparatus for carrying out this invention, the mandrel is supported by an arm that is pivotally mounted at a point spaced from the mandrel. Connected to said arm, at the pivot point for rotation therewith, is a shaft which comprises a part of the hydraulic damper. The shaft extends through a liquid-tight chamber, of generally cylindrical form, which is filled with a liquid such as oil. The chamber is divided into two sections by means of a stationary rectangular plate that extends from the walls of the chamber almost into contact with the shaft, and by a rectangular vane which is fastened to the shaft and extends almost into contact with the walls of the chamber. The movement of the arm supporting the mandrel will cause the shaft and the vane fastened thereto to rotate in the oil-filled chamber forcing the oil in said chamber to flow through the clearance between the said vane and walls of the chamber. By selecting a suitable clearance between the vane and the walls of the chamber, the flow of oil through said clearance will impart the desired resistance to the movement of the arm. Because the clearance between the vane and the walls of the chamber through which the oil flows comprises a series of elongated rectangular apertures, it has been found that there is a higher resistance to the flow of oil therethrough than through a circular aperture having the same area as the total area of the rectangular apertures. As a result, when using elongated rectangular apertures it is possible to obtain the desired resistance to movement with apertures having a relatively large total area so that the clearances between the vane and the walls of the chamber may be made large enough to present no problem for commercial production.

To render the hydraulic damper substantially inopera-

tive during the movement of the yarn package to the doffing position, the oil-filled chamber may be given a non-circular contour over a portion of its periphery so as greatly to increase the clearance between said vane and the walls of said chamber during such movement. The clearance between the vane and the walls of the chamber may be reduced again, immediately before the vane reaches a position corresponding to the doffing position, so as to cushion the movement of the yarn package to the doffing position. To reduce the resistance to the movement of the yarn package from the doffing position back to the winding position, a check valve may be provided which will permit the oil to flow from one section of the chamber to the other section. By regulating the loading on said check valve it is possible to impart any desired degree of resistance to the movement of the yarn package to the winding position.

A preferred embodiment of this invention is shown in the accompanying drawings wherein

Fig. 1 is a front elevational view, partly in section, of a horizontal yarn winder including the hydraulic damper of this invention.

Fig. 2 is a cross-sectional view, taken on the line 2—2 in Fig. 1, in the direction of the arrows.

Fig. 3 is a detail cross-sectional view, on an enlarged scale, of the hydraulic damper, taken on the line 3—3 in Fig. 1, in the direction of the arrows, and

Fig. 4 is a detail cross-sectional view, of the pressure relief cylinder, taken on the line 4—4 in Fig. 3, in the direction of the arrows.

Referring now to the drawing, the reference numeral 11 designates a machine frame provided with a boss 12 in which is rotatably journaled a shaft 13 driven by any suitable means (not shown). The shaft 13 carries a drive roll 14 which is adapted to frictionally engage the surface of a yarn package 15, mounted on a freely rotatable mandrel 16, for the purpose of rotating said yarn package. While the mandrel 16 may be of any suitable design, one design that has been found highly satisfactory is that shown in S. A. Petersen and H. Chow application S. No. 335,013, filed February 4, 1953, now Patent No. 2,733,874, issued February 7, 1956. During the actual winding operation, the rotation of the drive roll 14 causes the yarn package 15 to rotate, drawing a yarn 17 from any suitable source (not shown) onto the said yarn package through a yarn guide 18 which is traversed by any suitable traversing mechanism, not shown, to distribute the yarn onto the yarn package 15. To clean any waste yarn or other foreign matter from the surface of the drive roll 14 there is provided a brush 19 bearing against the said roll and supported by means of a fitting 21 that is fastened to a bar 22 extending through the machine frame 11. The brush 19 has interwoven with its normal bristles a small number of metallic bristles which function as electrical conductors to drain any static charges that may accumulate on the surface of the roll 14.

The mandrel 16 is supported for free rotation on a shaft 23 fastened to an arm 24 that is pivotally mounted at its lower end between a fitting, indicated generally by reference numeral 25, and a hydraulic damper, indicated generally by reference numeral 26. The pivotal mounting of the arm 24 permits the mandrel 16 carrying the yarn package 15 to be moved away from the drive roll 14 as the diameter of the yarn winding on said yarn package increases and to be moved entirely clear of the drive roll 14 for doffing and donning the yarn package 15. Pivotally fastened to the upper end of the arm 24 by means of a pin 27 is a handle 28 which can be used to rotate the arm 24 so as to bring the yarn package 15 into contact with the drive roll 14 or to move it away from said drive roll. At its lower end, the handle 28 is provided with a projection 29 which will function to brake the rotation of the mandrel 16 when the handle 28 is pivoted about the pin 27 as more fully described

in the Petersen et al. application referred to above. A stop 31 provided on the arm 24 acts to limit the return movement of the handle 28 and projection 29 with respect to the mandrel 16. The arm 24 is provided at its lower end with a lip 32 which abuts against a stop 33 projecting from the machine frame 11 when the arm 24 is rotated to the extreme right as shown in dotted lines 24" in Fig. 2 of the drawings to limit the maximum movement of the said arm in the direction away from the roll 14.

The fitting 25 comprises an apertured rib 34 on the machine frame 11 and a screw 35 threaded through the aperture in said rib. The screw 35 is provided with a tapered end 36 that fits into a tapered seat 36' in the arm 34 to provide one support for said arm. The hydraulic damper 26 comprises a damper assembly, indicated generally by reference numeral 37 and which will be described below, having a shaft 38 projecting therefrom and received in a bore 39 extending through the arm 24. The shaft 38 is fastened to the arm 24 by means of a set screw 41 so that the shaft and arm will turn as a unit. As another support for the arm 24 there is provided an annular collar 42 concentric with the shaft 38 and positioned between the damper assembly 37 and the arm 24. The internal diameter of the annular collar 42 is greater than the external diameter of the shaft 38 so that said shaft may rotate freely in said collar. The annular collar 42 is provided with a tapered end 43 that fits into a tapered seat 44 in the arm 24 to provide a second support for said arm. A proper fit may be obtained between the tapered ends 36 and 43 and the tapered seats 36' and 44, respectively, and any play or wear between said members may be readily corrected, by adjusting the position of the screw 35, which, once adjusted, may be held securely in place by means of a screw 45 which is adapted to clamp split ends 46 of the apertured rib 34 to prevent movement of the said screw 35.

The damper assembly 37 comprises a cylindrical member 47 having an open end adapted to be closed by a cover 48, a gasket 49 being provided between member 47 and cover 48 to form a liquid tight chamber 51. The chamber 51 may be filled with oil supplied through a petcock 52. The shaft 38 extends through the center of the chamber 51, being journaled for rotation in the member 47 and the cover 48, and being provided with spaced grooves 53 extending around its periphery. The grooves 53 are adapted to receive suitable packing material, as shown at 54, to prevent the leakage of oil from said chamber 51.

Fastened to the shaft 38, by means of screws 55, and moveable therewith is a vane 56 of rectangular shape which extends almost into contact with the inner walls of the chamber 51. Also positioned in the chamber 51 is a stationary plate 57 of rectangular shape that is held in place by means of screws 58 that extend through the walls of the chamber 51. One end of stationary plate 57 is in contact with the inner wall of the chamber 51 and is slightly spaced from the shaft 38, the construction of said stationary plate being such that it acts, together with the vane 56, to divide the chamber 51 into two sections. When the winding of a yarn package 15 is to begin, the center line of the arm 24 will be in the position shown by broken line 24' (Fig. 2), with the empty yarn package support 15' bearing against the drive roll 14. At this time, the vane 56 will be in the position 56' shown in Fig. 3 of the drawings. As the yarn 17 is wound onto the yarn package 15, the diameter of the said yarn package 15 will gradually increase thereby causing the arm 24 to rotate about its pivotal supports in a clockwise direction as viewed in Fig. 2 of the drawings. The rotation of the arm 24 will cause the shaft 38 and the vane 56 fastened thereto to rotate in a clockwise direction. During the slow rotation of the shaft 38 and the vane 56 caused by the increase in the diameter of the yarn package 15, the oil in the chamber 51 will flow past the clearance formed between the vane 56 and the

walls of said chamber without imposing any considerable resistance to the movement of said shaft 38. If, however, any high spots or other irregularities should develop in the winding of the yarn package 15 which would tend to cause the said yarn package 15 to bounce away from the drive roll, there will be a tendency for the arm 24, and the shaft 38 on the vane 56 secured thereto to move with a sudden, jerky movement. The resistance to the flow of oil through the clearance between the vane 56 and the wall of the chamber 51 will effectively prevent such sudden, jerky movements and, upon addition of further winding to the yarn package, will also tend to eliminate the high spots or other irregularities from the yarn package 15 and restore said yarn package to a truly circular cross-section.

When the winding of a yarn package 15 is complete, the said yarn package will have a diameter as shown by 15" (Fig. 2), the center line of the arm 24 will have moved to the position 24" and the vane 56 will have moved to the position shown in full lines in Fig. 3 of the drawing. At this time the operator, in order to move the yarn package 15 away from the drive roll to a doffing position, will grasp the handle 28 and move the arm 24 in a clockwise direction, as viewed in Fig. 2 of the drawings. To eliminate the resistance to such movement which would exist if it were necessary to force the oil in the chamber 51 through the small clearance between the vane 56 and the wall of the chamber 51, the chamber 51 is given a non-circular contour at 59 to increase the clearance between the vane 56 and the wall of the chamber 51. As a result, there will be relatively little resistance to the movement by the operator of the arm 24 to the doffing position. However, to prevent the lip 32 from striking the stop 33 with sufficient force to damage one or both of said elements, the clearance between the vane 56 and the wall of the chamber 51 is reduced so that there is again a considerable resistance to the movement of the arm 24 immediately prior to the contact between the lip 32 and the stop 33. Through this design, the arm 24 will move slowly to its doffing position 24" (Fig. 2) at which point the vane 56 will be in the position 56" (Fig. 3).

The plate 57 is provided with a spring-loaded check-valve 61 which will open to permit oil to flow from one side of said plate to the other side of said plate if the pressure developed in the chamber 51 at any time during the movement of the vane 56 from the starting to the doffing position should become excessive.

After the doffing of the yarn package 15, a fresh yarn package support is placed on the mandrel 16 and the operator moves the arm 24 back to the starting position to begin the winding of another yarn package 15. To permit said movement to be made quickly and without the use of excessive force, the vane 56 is provided with a spring-loaded check-valve 62 which will permit oil to flow from one side of said vane to the other side of said vane when the pressure in the chamber 51 developed by said movement exceeds a predetermined value. Through the presence of the spring-loaded valve 62, the force necessary to move the arm 24 to the starting position can be kept low. Yet by properly selecting the loading spring of said valve a sufficient resistance to said movement may be developed to prevent the yarn package 15 from coming into contact with the drive roll 14 with a force so great as to damage one or both of said members.

For best results, it is desirable that the chamber 51 be completely filled with oil at all times. One technique, that has been highly successful in effecting such complete filling, is to enter the oil into the chamber 51 at a temperature below normal so that as the oil warms to normal temperature it will expand and develop a pressure in said chamber. To prevent the pressure in the interior of the chamber 51 from becoming excessive through the expansion of the oil caused by the heat generated during

operation, there is provided in the closed end of the member 47, a piston 63 which rides in a bore 64 and is urged into the chamber 51 by a spring 65. Actual entry of the piston 63 into the chamber 51 is prevented by the plate 57 which overlies a portion of the bore 64 and acts as a stop. When the pressure of oil in the chamber 51 increases, the piston 63 will be forced into the bore 64 against the action of the spring 65, permitting the oil to expand, while when the pressure of oil in the chamber 51 decreases the spring 65 will force the piston 63 outwardly in the bore 64 returning the oil to the chamber 51 proper. To prevent leakage of oil, the piston 63 is provided around its periphery with a groove 66 in which is positioned packing material 67.

It is to be understood that the foregoing detailed description is given merely by way of illustration and that many variations may be made therein without departing from the spirit of my invention.

Having described my invention what I desire to secure by Letters Patent is:

1. A winder for yarns comprising a rotatable mandrel for supporting a yarn package, a drive roll for driving the yarn package through frictional contact with the surface of the yarn package, a damper operatively connected to the mandrel for interposing a resistance to movements of said mandrel, said mandrel being moveable from winding position with the yarn package in contact with the drive roll to a doffing position with the yarn package out of contact with the drive roll, and means for reducing the resistance by the damper to the movement of the mandrel during at least a portion of the movement of the mandrel from the winding to the doffing position.

2. A winder for yarns comprising a rotatable mandrel for supporting a yarn package, a drive roll for driving the yarn package through frictional contact with the surface of the yarn package, a damper operatively connected to the mandrel for interposing a resistance to movements of said mandrel, said mandrel being moveable from a winding position with the yarn package in contact with the drive roll to a doffing position with the yarn package out of contact with the drive roll, means for reducing the resistance by the damper to the movement of the mandrel during at least a portion of the movement of the mandrel from the winding to the doffing position, and means for increasing the resistance by the damper to the movement of the mandrel immediately prior to the movement of the mandrel into the doffing position to cushion the movement of the mandrel into the doffing position.

3. A winder for yarns comprising a pivotally mounted arm, a rotatable mandrel for supporting a yarn package fastened to said arm at a position spaced from the pivot point, a drive roll for driving the yarn package through frictional contact with the surface of the yarn package, a hydraulic damper operatively connected to the arm for interposing a resistance to movements of said arm, said arm being movable from a winding position with the yarn package in contact with the drive roll to a doffing position with the yarn package out of contact with the drive roll, and means for reducing the resistance by the hydraulic damper to the movement of the arm during at least a portion of the movement of the arm from the winding to the doffing position.

4. A winder for yarns comprising a pivotally mounted arm, a rotatable mandrel for supporting a yarn package fastened to said arm at a position spaced from the pivot point, a drive roll for driving the yarn package through frictional contact with the surface of the yarn package, a hydraulic damper operatively connected to the arm for interposing a resistance to movements of said arm, said arm being moveable from a winding position with the yarn package in contact with the drive roll to a doffing position with the yarn package out of contact with the drive roll, means for reducing the resistance by the hydraulic damper to the movement of the arm during at least a portion of the movement of the arm from the

winding to the doffing position, and means for increasing the resistance by the hydraulic damper to the movement of the arm immediately prior to the movement of the arm into the doffing position to cushion the movement of the arm into the doffing position.

5. A winder for yarns comprising a pivotally mounted arm, a rotatable mandrel for supporting a yarn package fastened to said arm at a position spaced from the pivot point, a drive roll for driving the yarn package through frictional contact with the surface of the yarn package, a hydraulic damper operatively connected to the arm for interposing a resistance to movements of said arm, said arm being moveable from a winding position with the yarn package in contact with the drive roll to a doffing position with the yarn package out of contact with the drive roll, means for reducing the resistance by the hydraulic damper to the movement of the arm during at least a portion of the movement of the arm from the winding to the doffing position, means for increasing the resistance by the hydraulic damper to the movement of the arm immediately prior to the movement of the arm into the doffing position, and means reducing the resistance by the hydraulic damper to the movement of the arm from the doffing position to the winding position.

6. A winder for yarns comprising a pivotally mounted arm, a rotatable mandrel for supporting a yarn package fastened to said arm at a position spaced from the pivot point, a drive roll for driving the yarn package through frictional contact with the surface of the yarn package, a chamber having a liquid therein, a vane positioned in said chamber and spaced from the wall of said chamber to form an aperture through which the liquid in the chamber can flow on movement of the vane, means operatively connecting the arm to the vane whereby movements of the arm will cause movements of the vane and thereby interpose a resistance to the movement of the arm, said arm being moveable from a winding position with the yarn package in contact with the drive roll to a doffing position with the yarn package out of contact with the drive roll, and said chamber being contoured to provide an increased clearance between the vane and the wall of the chamber during at least a portion of movement of the arm from the winding to the doffing position to decrease the resistance to the movement of the arm from the winding to the doffing position.

7. A winder for yarns comprising a pivotally mounted arm, a rotatable mandrel for supporting a yarn package fastened to said arm at a position spaced from the pivot point, a drive roll for driving the yarn package through frictional contact with the surface of the yarn package, a chamber having a liquid therein, a vane positioned in said chamber and spaced from the wall of said chamber to form an aperture through which the liquid in the chamber can flow on movement of the vane, means operatively connecting the arm to the vane whereby movements of the arm will cause movements of the vane and thereby interpose a resistance to the movement of the arm, said arm being moveable from a winding position with the yarn package in contact with the drive roll to a doffing position with the yarn package out of contact with the drive roll, said chamber being contoured to provide an increased clearance between the vane and the wall of the chamber during at least a portion of movement of the arm from the winding to the doffing position to decrease the resistance to the movement of the arm from the winding to the doffing position, and said chamber being contoured to provide a reduced clearance between the vane and wall of the chamber immediately prior to movement of the arm into the doffing position to cushion the movement of the arm into the doffing position.

8. A winder for yarns comprising a pivotally mounted arm, a rotatable mandrel for supporting a yarn package fastened to said arm at a position spaced from the pivot point, a drive roll for driving the yarn package through

frictional contact with the surface of the yarn package, a chamber having a liquid therein, a vane positioned in said chamber and spaced from the wall of said chamber to form an aperture through which the liquid in the chamber can flow on movement of the vane, means operatively connecting the arm to the vane whereby movements of the arm will cause movements of the vane and thereby interpose a resistance to the movement of the arm, said arm being moveable from a winding position with the yarn package in contact with the drive roll to a doffing position with the yarn package out of contact with the drive roll and back again, and a check valve to permit liquid to flow from one side of said vane to the other side of said vane when the arm is moved from the doffing position to the winding position to decrease the resistance to movement of the arm from the doffing position to the winding position.

5 9. A winder for yarns comprising a pivotally mounted arm, a rotatable mandrel for supporting a yarn package fastened to said arm at a position spaced from the pivot point, a drive roll for driving the yarn package through frictional contact with the surface of the yarn package, a chamber having a liquid therein, a vane positioned in said chamber and spaced from the wall of said chamber to form an aperture through which the liquid in the chamber can flow on movement of the vane, means operatively connecting the arm to the vane whereby movements of the arm will cause movements of the vane and thereby interpose a resistance to the movement of the arm, said arm being moveable from a winding position with the yarn package in contact with the drive roll to a doffing position with the yarn package out of contact with the drive roll and back again, and a check valve to permit liquid to flow from one side of said vane to the other side of said vane when the arm is moved from the doffing position to the winding position to decrease the resistance to movement of the arm from the doffing position to the winding position.

from one side of said vane to the other side of said vane when the arm is moved from the doffing position to the winding position to decrease the resistance to movement of the arm from the doffing position to the winding position, a check valve in said plate to permit liquid to flow from one side of said plate to the other side of said plate when the pressure on the liquid to one side of said plate exceeds a given value and a pressure relief comprising a spring loaded piston moveable in a cylinder opening into said chamber to compensate for fluctuations in the pressure of the liquid in the chamber.

11. A damper comprising a liquid tight chamber of generally cylindrical form having a liquid therein, a shaft extending through said chamber, a stationary plate extending from said shaft into contact with the wall of the chamber, a rotatable rectangular vane fastened to said shaft and having a longitudinal edge extending almost into contact with the wall of the chamber to form an elongated aperture through which the liquid in the chamber can flow on angular movement of the vane to interpose a resistance to movement of the vane, said plate and said vane separating the chamber into two sections, said chamber being contoured to provide an increased clearance between an end of the vane and the wall of the chamber to decrease the resistance to the movement of said vane during a portion of said movement, and said chamber being contoured to provide a reduced clearance between the vane and wall of the chamber adjacent one limit of the movement of the vane to cushion the movement of

the vane to said limit, a check valve in said vane to permit liquid to flow from one side of said vane to the other side of said vane when the vane is moved in a given direction to decrease the resistance to movement of the vane in said direction, a check valve in said plate to permit liquid to flow from one side of said plate to the other side of said plate when the pressure on the liquid to one side of said plate exceeds a given value, and a pressure relief comprising a spring loaded piston moveable in a cylinder opening into said chamber to compensate for fluctuations in the pressure of the liquid in the chamber.
